a corporation of New York

Application March 9, 1928, Serial No. 260,364
Renewed October 20, 1934

16 Claims. (Cl. 274—21)

This invention relates to dictating machines, and in a more specific aspect to dictating machines of the transcribing type.

An object of this invention is to facilitate the operation of the device, to improve its performance, and to decrease the assembling cost; one of the outstanding improvements herein disclosed being the provision of means for positively centralizing the stylus relative to the sound-box after the back-spacing operation has been performed, said means being actuated by the back-spacing means.

Another object of this invention is to provide means to centralize the stylus and back-space the carriage by the operation of a single lever.

In the accompanying drawing, which illustrates one embodiment of this invention—

Figure 1 is a top plan view of parts shown in Fig. 2, the sound-box and frame portions being shown in dotted lines.

Fig. 2 is a side sectional view of part of a dictating machine, showing one embodiment of the present invention as applied thereto.

The phonographic machine shown in the accompanying drawing comprises a carriage 10 movable longitudinally of the machine frame on carriage rods 11 and 12, forming part of the frame of the machine, under the influence of a rotatable feed-screw 13 when engaged by a feed-nut 14. The carriage 10 is provided with a head portion 15 adapted to support a sound-box 16 for reproducing the sound recorded on a record 17 adapted to be mounted on a record-support 18 rotatably supported on the frame. The sound-box 16 as usual comprises a diaphragm connected by a link 19 to a lever 20 which has, at its forward end, a reproducing stylus 21 which engages the record 17.

For the purpose of allowing the stylus 21 to move vertically, i. e. toward and from the record-support 18, to accommodate itself to records of different thicknesses, the stylus lever 20 is pivotally mounted at 22 on a floating support 23 having a horizontal pivot 24 in a plate 25 which is fixed in the carriage frame against vertical movement. The stylus is normally held in engagement with the record 17 by the weight of the floating support 23 and by the tension of a spring 26 which is fixed at one end to the plate 25 and at its other end to the support 23.

As usual, but in a new way below referred to, the support 23 and related stylus 21 have only a limited downward movement under the influence of the support and spring 26.

55 The stylus is also allowed to track the record, i. e. laterally follow the grooves of the record to compensate for any minute differences that may exist between the record grooves and the feed-screw 13. To accomplish this, the lever 25 is provided with a pivot-pin 27 which is supported

at its upper end in a sleeve 28 and has a bearing at its lower end in a bracket 29. The side walls 29 and 31 of the bracket 29 are adapted to limit the range of pivotal movement of the lever 25 about the axis of the pin 27 and allow proportionate movement of the floating support 23 which it carries. Thus, it will be seen that the floating support 23, which carries the stylus 21, has only a limited range of free lateral movement in which to track the record.

When no record is upon the record-support, the carrier 23 and stylus 21 drop to the limit of downward movement. However, when a new record is slid on to the record-support, the record end engages one side of a stylus guard 32 fixed to the floating support 23, the sides of the guard being angularly disposed relative to the surface of the record-support. As the operator pushes the record further on to the record-support, the engagement of the record-end with the side of the guard 32 pushes the support 23 sideways until movement is stopped by one of the side walls 30, 31, continued movement of the record on the record-support causes the end of the record to act as a cam on the guard 32 to force up the carrier 23 and related stylus 21 until the record end engages the stylus 21 to complete the raising of the stylus to the surface of the record. The record is then further moved to engage a flange portion (not shown) of the record-support. In this operation, the stylus 21 and floating support 23 are moved laterally with respect to the transverse center line of the sound-box, and remain in this condition until the record-support is caused to rotate, whereupon the carrier 23, due to its balanced mounting, and partially under the influence of a spring 26 and the natural drag of the stylus on the record 17, causes it to immediately and automatically assume a substantially central position with respect to the sound-box 16.

40 After a record is placed on the record-support 18, it may be caused to rotate by any method of control common to this type of machine. The feed-screw 13 rotates coordinately with the record-support and causes the carriage to move longitudinally of the record, whereupon the stylus 21, which is then in engagement with the record, cooperates with the diaphragm to reproduce any sound which may be recorded upon the record.

45 In using the machine, the operator sometimes finds it necessary to have a very small portion of the record surface repeated, and consequently desires to back-space the carriage a small extent. To facilitate this, dictation machines have heretofore been, and the machine of the present invention is provided with mechanism to back-space the carriage. The back-spacing mechanism selected for the purpose of illustrating the present invention comprises a back-space lever 33 rotatably mounted on a tubular bearing 34.

forming part of the carriage 10, and the lever 33 is provided at its top portion with a lug 35 pivotally carrying a pawl 36 which has a limited range of movement. This lever is normally held in inoperative position as seen in Fig. 1, by a spring 37 which is enclosed in a collar 38 held on the tubular bearing 34 by a screw 39.

When the back-space lever 33 is operated, the pawl 36 engages a rack 40 secured to suitable supports on the frame and forces the carriage 10 backwardly a predetermined extent. To further back-space the carriage, the back-space lever 33 may be repeatedly operated. The back-spacing mechanism, as far as above described, is of usual form such as is disclosed in the patent to Macdonald, No. 1,030,740, June 25, 1912. In the present case, however, the back-spacing mechanism has been modified to obtain several results which will hereinafter be described.

It should be especially noted that the present invention provides on the pawl 36 means adapted to disengage automatically the pawl from operative relationship with the rack 40 after the back-space lever 33 has been moved a predetermined extent, thus allowing continued movement of the back-space lever without further moving or back-spacing the carriage. In the present preferred embodiment of the invention, this is accomplished by providing a cam 41 preferably made integral with the pawl to engage the tops of the rack teeth or other portion of or near the rack after the pawl proper has back-spaced the carriage a predetermined extent, the cam then acting as a fulcrum to move the pawl out of engagement with the rack teeth.

Because the kind of feed-mechanism shown in the Macdonald patent is illustrated herein, it is necessary to disengage the feed-nut 14 from the feed-screw 13 while the carriage is being back-spaced. This is accomplished, according to the present preferred embodiment of this invention, by the provision of a cam portion 42 formed integral with a tubular portion 43 of the back-space lever 33 adapted to engage an extension 44 on the pivotally mounted feed-nut 14. As shown in Fig. 1, the relationship of these two parts is such that normally the feed-nut is allowed to move and engage the feed-screw under the influence of a spring 45, but upon depression of the back-space key 33 the feed-nut is cammed out of engagement with the feed-screw 13, after which the pawl engages the rack to back-space the carriage a predetermined extent. After this back-spacing has been finished, the pawl, according to this invention, is moved out of engagement with the rack by the cam portion 41 of the pawl, and upon further movement of the back-space lever, the extension 44 permits the feed-nut 14 to again move under the influence of its spring 45 and engage the feed-screw. The purpose of the second feed-nut engaging position will hereinafter be more fully described. Thus, the present invention provides a feature of particular importance for, by controlling the feed-nut in this direct manner, machine construction and operation are simplified, as it is unnecessary to provide the usual auxiliary lever 46 shown in dotted lines in Fig. 2, the purpose of which, as is well known to those familiar with the art, is to condition the machine to be moved by hand.

Supported on the head 15 by studs 48 and 49, which pass through apertures 50, is a slide or bar 47. These apertures permit a limited range of sliding movement of the bar 47. A spring 75 51 fits within an aperture 51' in the carriage

head 15, one end engaging an end of the aperture as at 52' and the other end engaging a struck-up portion 52 of the bar 47, and serves to normally keep the bar in inoperative position as shown in Figs. 1 and 2. The bar is provided with a slot 53 at its lower end which accommodates an upstanding pin portion 54 of a pawl stud 55 and serves as an operating connection between the back-space lever 33 and the bar 47. This slot is of sufficient length to allow the back-space lever 33 to be rotated until the pawl has performed its normal back-spacing function, and the cam portion 41 of the pawl moves the pawl to inoperative position before the pin 54 engages the end of the slot 53 to move the bar 47 upon further depression of the lever 33.

At the opposite end of the bar 47 there is provided a struck-up member 56 which is held thereon by pins 57. This member is struck-up to form a V 58, the apex of which is formed as a slot 59, the slot portion 59 being on the center line transversely of the carriage with respect to the sound-box 16. This member 56 serves to positively centralize the stylus 21 with relation to the sound-box in a manner hereinafter described.

Although in its preferred form as shown in the illustrated embodiment of the invention, the slot 59 is centered upon the transverse center line of the sound-box, it will be understood that a degree of tolerance may be allowed in the location and width of this slot so long as the position and width of the slot are such as to cause the stylus to assume a position relatively central with respect to the limits of its range of free lateral movement.

The bar 47 is operated to positively centralize the stylus incidental to the operation of back-spacing the carriage with the lever 33. When the operator desires to back-space the carriage, he merely presses on a finger-piece 63 of the back-space lever causing the pawl 36 to operate in the manner hereinbefore described. After this, the pin 54 engages the end of the aperture 53 to move the bar 47 forwardly against the pressure of the spring 51. When the carriage is so back-spaced, the floating support 23, because of the engagement of the stylus 21 with the record, lags behind the carriage. However, when the bar 47 moves, a pin 61 on the floating support engages the V 58 and slot 59 to move the stylus to centralized position. The side walls of the V serve to limit lateral movement of the support 23 relative to the sound-box by the pin 61 engaging either wall as seen in Fig. 2, and a cross strip 58' stops the drop of the pin 61 and thus limits movement of the stylus and support toward the record-support 18.

As the operator depresses the finger-piece 60 of the back-space lever, further rotation of the tubular portion 43 after the pawl 36 has performed the back-spacing function, causes the pin 54 to engage the end of the aperture 53 and pull the bar forwardly against the pressure of the spring 51. The side walls of the V 58, engaging the end of the pin 61 of the floating support, move the support toward the transverse center line of the sound-box, and, with the continued depression of the finger-piece, the V-shaped member 56 on the bar 47 moves forwardly until the pin 61 enters the slot portion 59 of the member 56. In this position the carrier 23 and related stylus are positively centralized relative to the sound-box.

Thus it will be seen that with the mechanism, 75

according to the present invention, the carriage is back-spaced a predetermined extent; the pawl is rendered inoperative by being forced out of engagement with the rack 40; and the V and

5 slot member 56 on the bar picks up the floating support and moves the same to a centralized position with respect to the sound-box. The slot 59 is proportioned to prevent lateral movement of the pin when in this position, but allows a limited up-and-down movement of the stylus and floating support with respect to the record. Thus it will be seen that as the support 23 and related stylus is moved from the lagging position to a centralized position with respect to the sound-box, the stylus 21 is free to ride up and down over the record grooves and thus there is no danger of marring or damaging the recorded surface of the record. This method of centralizing the stylus is very advantageous, for the action 10 is positive and by it a very simple and direct control is provided which greatly facilitates operation of the machine.

It should be noted at this point that a dwell

25 62 and a second cam portion 63 are provided on the tubular section 43 of the back-space lever 33. The dwell 62 is adapted to allow the feed-nut to rotate and engage the feed-screw again momentarily after the carriage 10 has been back-spaced and while the floating support pin 61 engages the slot 59. The purpose of this dwell is to compensate for minor differences between the spacing of the carriage and the relationship of the feed-nut with the feed-screw, so that these two members will be positively in line when the 30 back-space lever is fully released, and thus the carriage 10 will not be further moved and adversely affect the centralized position of the stylus and floating support 23, as would occur if the feed-nut and feed-screw moved longitudinally relative to each other if they were only brought into engagement after the pin 61 is disengaged from the slot 59.

40 Besides accomplishing the function of automatically back-spacing the carriage a small predetermined extent as just described, the back-space lever 33 can, according to the present invention, be further utilized for the purpose of moving the carriage forwardly or backwardly major extents by the simple expedient of merely pushing the carriage in either desired direction while the back-space lever 33 is fully depressed. With this lever so depressed, the pawl 36 will be in disengaged position, i. e. with the cam portion 41 on the tops of the rack teeth or other 45 55 abutment and the centralizing member 56 of the slide will be in operative position holding the floating support 23 and related stylus against lateral movement while allowing free up-and-down movement.

60 With the machine so conditioned, the carriage may be moved to any desired position longitudinally of the record, as there will be no interference to the free movement of the carriage, for, due to the engagement of the pawl cam 41 on the 65 rack teeth, the pawl will merely ride over the tops of these teeth, and the feed-nut, which is now held out of engagement with the feed-screw by the cam portion 63, cannot impede this free movement.

70 While it is possible to forward or back-space the carriage in this manner for movements of large extent, the advantageous feature of having the stylus and carrier positively centralized with respect to the sound-box is maintained, for when 75 the lever is released, the feed-nut 14 will be in

proper relationship with the feed-screw and the stylus 21 and carrier 23 will be positively centralized with respect to the sound box after the centralizing member is moved to inoperative position.

5 Variations and modifications may be made within the scope of this invention, and portions of the improvements may be used without others.

Having thus described the invention, what is claimed as new and for which it is desired to obtain Letters-Patent, is:—

1. In a phonograph, the combination of a rotatable record-support; a carriage movable along said record-support; a sound-box on said carriage; a stylus on the sound-box having a limited range of free tracking movement relative to the sound-box along said record-support; means for back-spacing the carriage along the record-support while the stylus is in record-engaging position; and means operated by said back-spacing means to centralize the stylus relative to the sound-box after the carriage has been back-spaced.

2. In a phonograph, the combination of a rotatable record-support; a carriage movable along said record-support; a sound-box on said carriage; a stylus on the sound-box having a limited range of free tracking movement relative to the sound-box; means for back-spacing the carriage while the stylus is in record-engaging position; and means operated by said back-spacing means to centralize the stylus relative to the sound-box after the carriage has been back-spaced, said means allowing free movement of the stylus relative to the sound-box toward and from the record-support.

3. In a phonograph, the combination of a rotatable record-support; a carriage movable longitudinally of the record-support; a sound-box on the carriage; a stylus carrier pivotally mounted on the sound-box and having a limited range of lateral movement relative thereto; means adapted to centralize the stylus within said range of lateral movement; carriage back-spacing means comprising a pivoted lever adapted to effect back-spacing in one part of its movement and to actuate the means to centralize the stylus relative to the sound-box upon further movement.

4. In a phonograph, the combination of a carriage, a sound-box on said carriage, a stylus carried by the sound-box and having a limited range of free lateral movement relative to the sound-box, means to backspace the carriage, and means operatively associated with said backspace means adapted to move the stylus to a predetermined central position, said means operating after the carriage has been backspaced.

5. In a phonograph, the combination of a carriage; a sound-box on said carriage; a stylus carried by the sound-box and having a limited range of free lateral movement relative to the sound-box; means to back-space the carriage; and means operatively connected with said backspace means to cause the stylus to assume and hold a predetermined position relative to the sound-box after the carriage has been back-spaced.

6. In a phonograph, the combination of a frame, a rotatable record-support on the frame, a carriage longitudinally movable along the frame, a sound-box on the carriage, a stylus mounted on the sound-box, a floating support for the stylus having a limited range of free tracking movement laterally relative to the sound-box, means to backspace the carriage, and means operatively associated with said backspace means and acting

- after the carriage has been backspaced unconditionally to move the floating support to a predetermined position within said range of free lateral movement.
7. In a phonograph, the combination of a frame; a carriage movable on the frame; a stylus movably mounted on the carriage; carriage advancing means comprising a feed-screw on the frame and a cooperating feed-nut on the carriage; means for back-spacing the carriage comprising a lever on the carriage; means on the lever to first lift and then hold the feed-nut out of engagement with the feed-screw while the back-spacing operation takes place; and means actuated through movement of said lever to positively locate the stylus in a predetermined position relative to the carriage after the carriage has been backspaced.
8. In a phonograph, the combination of a frame; a carriage movable on the frame; carriage advancing means comprising a feed-screw on the frame and a cooperating feed-nut on the carriage; means for back-spacing the carriage comprising a lever pivotally mounted on the carriage; and means comprising a member provided with alternate cam and dwell surfaces and actuated by depressing the pivotally mounted lever to first lift and then hold the feed-nut out of engagement with the feed-screw while the back-spacing operation takes place and to allow return of the feed-nut into engagement with the feed-screw after the carriage has been back-spaced while the lever is in depressed position.
9. In a phonograph, the combination of a frame; a carriage movable on the frame; carriage advancing means comprising a feed-screw on the frame and a cooperating feed-nut on the carriage; means for back-spacing the carriage comprising a lever rotatably mounted on the carriage; and a cam on the rotatably mounted lever adapted to allow feed-nut engagement with the feed-screw when the lever is in normally non-actuated position, disengage the feed-nut from the feed-screw when the lever is rotated for back-spacing, allow feed-nut engagement with the feed-screw upon further rotation of the lever after the back-spacing operation has been performed, and again disengage the feed-nut from the feed-screw upon further rotation of the lever.
10. In a phonograph, the combination of a frame, a carriage movable on the frame, a sound-box on the carriage, a stylus, a floating support for the stylus movable laterally relatively to the sound-box, and a spring-biased member mounted on the sound-box and slidable away from its biased position to act directly on said floating support for positively centralizing the floating support with respect to its path of lateral movement.
11. In a phonograph, the combination of a frame, a carriage movable on the frame, a sound-box on the carriage, a stylus, a floating support for the stylus movable laterally relatively to the sound-box, and a spring-biased member mounted on the sound-box and slidable away from its biased position to act directly on said floating support for positively centralizing the floating support with respect to its path of lateral movement, and means on said member adapted normally to limit the lateral movement of the floating support.
12. In a phonograph, the combination of a frame, a carriage movable on the frame, a sound-box on the carriage, a stylus, a floating support for the stylus movable vertically and laterally relatively to the sound-box, and a spring-biased member mounted on the sound-box and slidable away from its biased position to act directly on said floating support for positively centralizing the floating support with respect to its path of lateral movement, and means on said member adapted normally to limit the lateral and downward vertical movement of the floating support.
13. In a phonograph, the combination of a support for a record; sound-reproducing means comprising a stylus mounted for a range of free lateral movement in which to track the record; manually operated means for shifting said stylus backwardly towards the beginning of the record by causing the same to skid or glide over the record-surface; and means operatively connected with said stylus-shifting means for causing the stylus to assume and hold a predetermined central position with relation to said sound-reproducing means after said backward movement has been effected without lifting the stylus from the record.
14. In a phonograph, the combination of a support for a record; sound reproducing means comprising a stylus mounted for a range of free lateral movement in which to track the record; means for shifting said stylus backwardly toward the beginning of the record by causing the same to skid or glide over the surface of the record; and means actuated independently of the bodily movement of said sound-reproducing means and operated by the means for shifting the stylus backwardly for causing the stylus to assume a central position in said range of free lateral movement after completion of backspacing movement.
15. In a phonograph, the combination of a support for a record; sound-reproducing means comprising a stylus mounted for a range of free movement in which to track the record; means for shifting said stylus upon the record by causing the same to skid or glide over the surface of the record; and means actuated independently of the bodily movement of said sound-reproducing means and operated by the means for shifting the stylus for causing the stylus to take a position within said range of free movement after completion of said shifting movement.
16. In a phonograph, the combination of a frame; a carriage movable on the frame; carriage-advancing means comprising a feed-screw on the frame and a cooperating feed-nut on the carriage; means for backspacing the carriage comprising a lever pivotally mounted on the carriage; means comprising a member actuated by depressing the pivotally mounted lever to first lift and then hold the feed-nut out of engagement with the feed-screw while the backspacing operation takes place and to allow return of the feed-nut into engagement with the feed-screw after the carriage has been backspaced while the lever is in depressed position; and means actuated through movement of said lever positively to lock the stylus in a predetermined position relative to the carriage after the said re-engagement of the feed-nut with the feed-screw.

ARTHUR A. JOHNSON.
